UNITED STATES PATENT OFFICE

117,825

DESIGN FOR A KNIFE HOLDER

Fred E. Smith, Stowe, Vt.

Application August 25, 1939, Serial No. 86,897

Term of patent 7 years

To all whom it may concern:

Be it known that I, Fred E. Smith, a citizen of the United States, residing at Stowe, in the county of Lamoille and State of Vermont, have invented a new, original, and ornamental Design for a Knife Holder, of which the following is a specification, reference being had to the accompanying drawing, forming a part thereof.

In the drawing:

I claim:

The ornamental design for a knife holder, as shown.

FRED E. SMITH.
